UNITED STATES PATENT OFFICE.

JAMES W. CAMPBELL, OF GERMANTOWN, ASSIGNOR TO FERGUSON
BROTHERS, OF NEW YORK, N. Y.

DESIGN FOR A HANGER FOR TOILET ARTICLES.

SPECIFICATION forming part of Design No. 19,485, dated December 17, 1889.

Application filed November 14, 1889. Serial No. 330,506. Term of patent 7 years.

To all whom it may concern:

Be it known that I, JAMES W. CAMPBELL, of Germantown, in the county of Columbia and State of New York, have invented and produced a new and original Design for a Hanger for Toilet Articles, &c., of which the following is a specification, reference being had to the accompanying drawings, forming a part thereof.

Figure 1 is a front view, and Fig. 2 a side view, of a hanger embodying my design.

The design consists of a bar A and an interrupted ring B, depending from said bar at

about the middle of the length thereof, the faces *a a* of said ring being substantially parallel with the length of said bar and the interruptional break *b* of the said ring being in its lower part.

What I claim as my design, and desire to secure by Letters Patent, is—

The design for a hanger, substantially as herein shown and set forth.

JAMES W. CAMPBELL.
